UNITED STATES PATENT OFFICE.

ELIJAH MOUNTFORD, OF TRENTON, NEW JERSEY.

DESIGN FOR TABLE-WARE.

SPECIFICATION forming part of Design No. 16,206, dated August 18, 1885.

Application filed May 21, 1884. Term of patent 7 years.

To all whom it may concern:

Be it known that I, ELIJAH MOUNTFORD, a citizen of the United States, residing at Trenton, in the county of Mercer and State of New Jersey, have invented a new and original Design for Articles of Table-Ware, of which the following is a full and clear description, reference being had to the accompanying drawings, which form a part of this specification, and in which drawings similar parts are indicated by similar letters of reference.

In the drawings, Figure 1 shows a side view of a cover-dish containing my design. Fig. 2 shows a top view of the cover; and Fig. 3 shows a top view of the dish, looking down into the interior thereof. These drawings show only a cover-dish and cover; but I can and do apply my design to all appropriate articles of table-ware.

20 In Fig. 1, A is the body of the dish. B is the cover, and B' the handles. The body of the dish is, as shown, in vertical outline ogee in shape. About the swell of the body A, I place a series or band of flutings, E. The 25 cover is surmounted by a plane, D, upon which is placed a handle, D'. This cover is, as shown at Fig. 2, in base outline a parallelogram in shape, having square corners and scalloped edges F. In Fig. 2 is also shown a top view 30 of the cover-handle. This handle is branched, each branch being provided with an ornamenteally-shaped foot, B², surmounted by a boss, B³. The upper side of the handle rises in a slightly pyramidal-shaped form to 35 and is surmounted by a central boss, B⁴.

In Fig. 3, G is the top of the rim of the dish. H is the bottom of the interior; A, the body, and E the top of the flutings, rising slightly above the swell of the body A. As will be seen by 40 the drawings, the dish is in base outline a parallelogram in shape, with square corners.

What I claim as my invention, and desire to secure by Letters Patent, is—

1. The design for an article of table-ware, such article having an ogee vertical outline 45 shape and a parallelogrammatic horizontal body outline shape, with square corners, as shown and described.

2. A design for an article of table-ware, such article having a vertical outline ogee-shaped, with flutings E thereon, as shown, and having a parallelogrammatic-shaped horizontal body outline shape, as shown and described.

3. A design for an article of table-ware, 55 such article having a vertical outline ogee-shaped, with flutings E thereon, as shown, and having a parallelogrammatic-shaped horizontal body outline, with square corners, as shown and described. 6c

4. A design for a cover for articles of table-ware, such cover a parallelogram in form, with square corners and scalloped edges, substantially as shown and described.

5. A design for a cover for articles of table-ware, such cover a parallelogram in form, 65 with square corners and scalloped edges, and provided with the handle B', substantially as shown and described.

6. A design for handles for articles of table-ware, such handles branched at the end, each branch provided with the ornamental foot B², with its boss B³, as shown, such handle surmounted by a pyramidal-shaped top with central boss, B⁴, as shown and described. 70

ELIJAH MOUNTFORD.
